UNITED STATES PATENT OFFICE

FREDERICK J. PETERS, OF BABYLON, NEW YORK

DESIGN FOR A PITCHER OR LIKE ARTICLE

Application filed August 11, 1931. Serial No. 40,827. Term of patent 7 years.

To all whom it may concern:

Be it known that I, FREDERICK J. PETERS, a citizen of the United States, residing at Babylon, in the county of Suffolk and State of New York, have invented a new, original, and ornamental Design for a Pitcher or Like Article, of which the following is a specification, reference being had to the accompanying drawings, forming part thereof.

I claim:

The ornamental design for a pitcher or like article, as shown.

FREDERICK J. PETERS.
